REMOVABLE TOP LIFT

Reuben P. Grant, Concord, N. H., assignor to
Beckwith Manufacturing Company, Boston,
Mass., a corporation of Massachusetts

Application January 21, 1933, Serial No. 652,801

4 Claims. (Cl. 36—36)

This invention relates to a shoe heel having a removable top lift and to a device by which the top lift can be removably fastened to the body of the heel. It is well-known that most people tend to wear the heels of their shoes unevenly, that is, the wear at one side is more rapid than at the other so that there is a tendency on the part of the heels to "run over". When a heel has thus worn down unevenly for even a short distance, the foot is thrown out of balance every time the heel contacts with the ground or floor on which the wearer of the shoe is walking or standing. This is specially true of heels having top lifts of relatively small area, as for example most of the comparatively high heels on ladies' shoes. In such cases, a small amount of running over of the heel results in a serious angle of tilt on the part of the shoe itself, since the slanting worn surface of the top-lift cannot oppose the tendency of the foot to tilt the shoe, which tendency is responsible in the first place for the running over of the heel. Such uneven wear should be corrected before it has gone far, but as this ordinarily entails a trip to the shoe repairer, it is usually neglected until the sole has worn through or until the tilt of the heel has become very pronounced. It is an object of the present invention to provide a shoe with an easily removable top lift on the heel so that it can be replaced by spare top lifts which may be sold with the shoe if desired and may be readily installed in place by the user. Hence, replacement can be made as frequently as required or desired by simply removing the old or worn top lift and replacing it with a new one.

35 In carrying out the invention, I provide inter-
engaging fastening members on the body of the
heel and on the top lift, these members being
arranged to permit the top lift to be slid into place
against the top face of the heel body, a spring
40 latch being provided to hold the top-lift in its cor-
rect position when it has been moved into regis-
try with the heel body. Provision is also made
for the insertion of a simple tool to release the
locking latch and to permit the top-lift to be
45 slid in the reverse direction to clear the heel body.
For a more complete understanding of the inven-
tion reference may be made to the disclosure
thereof in the following description of an em-
bodiment thereof, and on the drawing, of
50 which.—

Figure 1 is a side elevation of a shoe containing an embodiment of the invention.

Figure 2 is a fragmentary section on the line 2-2 of Figure 1.

Figure 3 is a section on the line 3-3 of Figure 2.

Figure 4 is a perspective view of a top lift for a heel, showing one of the fastening members secured thereto.

Figure 5 is a perspective view of a heel body, showing a cooperating fastening member secured thereto.

Figure 6 is an elevation of a tool for releasing the fastening device to permit removal of a top-lift.

In the manufacture of women's shoes, the heels often consist of a one-piece body member of wood, hollow metal, or other suitable material. The top of this heel body is customarily faced with a leather top-lift secured to the heel body by means of nails, or other equivalent fastening element. In the following description of a shoe containing an embodiment of the invention, the shoe is supposed to be in the usual upside down position for manufacture. Figure 1 illustrates a woman's shoe 10 having a heel consisting of a heel body 11 and a top lift 12. Instead of the usual nails for fastening the top-lift on the heel body, a fastening device is employed, according to the invention, which normally secures the top-lift in its proper place but which can be manipulated to release the top-lift for replacement. This fastening device may consist primarily of two cooperating members; an anchor plate 15 and a coupling plate 16. One of these plates is secured to the heel body, the other being 15 20 25 30

secured to the top-lift. As shown, the anchor plate is the one which is secured to the heel body, as illustrated in Figure 5. The heel body 11 is preferably provided with a recess 17 in its upper face, this recess being of sufficient area to receive the anchor plate or the coupling plate and being of a depth substantially equal to the combined thicknesses of the anchor and coupling plates so that when these plates are in face to face engagement, the surrounding face portions of the heel body and top-lift will engage each other closely. Figure 5 illustrates the anchor plate 15 as secured in the recess 17, the forward end of the plate 15 being just inside of the forward face or breast of the heel body. The plate 15 may be secured to the heel body as by a screw 29 and a pair of nails 21. The portion of the anchor plate 15 which is forward of the nails 21 is laterally cut away as at 22 forming a tongue 23 of reduced width, this tongue terminating in an upstanding end edge portion 25 which may be centrally notched as at 26. At the rear end of the plate 15 a stop 27 is provided which, as shown, 55

may consist of a turned-up end portion of the plate. As indicated in Figure 3 the anchor plate 15 may be of substantial thickness, in which case the tongue portion 23 is preferably thinner so as to be stiffly resilient. The side edges 30 of the anchor plate are free, that is, spaced from the bottom surface of the recess 17, so as to act as guide rails for the coupling plate 16. To this end, the anchor plate 15 may be laterally undercut at 31, as shown in Figure 2, or the bottom of the recess 17 may be locally cut away beneath the side edges 30 of the plate so as to allow clearance underneath these side edges for a purpose hereinafter set forth.

15. The coupling plate 16 is shown in Figure 4 as secured to the bottom face of the top lift as by a suitable number of rivets 35. The coupling plate is provided with suitable retaining elements by which it is secured to the anchor plate when the top lift is in position. These retaining elements may be in the form of side edge portions 36 of the plate 16 which are bent back so as to hook under portions of the anchor plate 15 as shown in Figure 2. The side edge portions 30 of the anchor plate are preferably left free and clear of the bottom surface of the recess 17 so as to provide clearance for the hooks or flanges 36 of the coupling plate 16. The parts are so arranged that when the top lift is slid rearwardly on the upper face of the heel body, the flanges 36 may engage under the free edges 30 of the anchor plate so that the top lift is held against the heel body as it is slid rearwardly. The anchoring plate is located so that when the rear end edge of the coupling plate engages the upturned end portion 27 of the anchor plate, the top lift is in proper registry with the heel body. The length of the coupling plate is preferably equal to the distance between the upturned end portion 25 of the tongue 23 and the upturned rear end edge 27 of the anchor plate. The lateral cut-outs 22 in the anchor plate 15 permit the flanges 36 of the coupling plate to pass the upturned end portion 25 of the tongue 23. In order to permit the central portion of the coupling plate 16 to pass the upturned flange 25 of the tongue, the tongue itself must be sprung downwardly so that the flanges 36 may engage under the free edges 30. When the coupling plate is moved all the way in so that it engages the stop 27, the end flange 25 springs up and thus acts as a locking latch to prevent reverse sliding movement by the coupling plate 16 away from the stop 27. The top lift is thus held firmly in place on the heel body. When it is desired to remove the top lift for replacement, a pointed tool 40 may be inserted in the notch 26, the forward edge of the plate 16 being centrally bevelled as at 41 to receive the point of the tool 40. Insertion of such a tool of suitable diameter wedges the tongue 23 downwardly a sufficient distance to move the flange 25 clear of the forward edge of the plate 16. The top lift may then be moved forwardly until the lateral flanges 36 are clear of the free edges 30 of the anchor plate. The top lift is then separate from the heel body.

It is evident that many variations and changes may be made in the specific embodiment of the invention herein shown and described by way

of example and not limitation, without departing from the spirit or scope of the invention as defined in the following claims.

What I claim is:

1. A shoe heel comprising a body member, a top-lift member, and means for releasably securing said members together, said means including an anchor plate secured to one member, said anchor plate having free side edge portions, an upturned rear edge portion, and a resilient tongue at its forward end terminating in an upturned portion, and a coupling plate secured to the other said member, said coupling plate having turned-back side edge portions engaging under said free edge portions of the anchor plate, said coupling plate also being of a length to fit snugly between the upturned end portions of said anchor plate when the top-lift is in correct position on the heel body.

2. A shoe heel comprising a body member, a top-lift member, and means for releasably securing said members together, said means including an anchor plate secured to one of said members and a coupling plate secured to the other said member and adapted to interlock with said anchor plate, said anchor plate having free side edge portions, an upstanding rear end edge portion, and a resilient latch portion at its forward end, said coupling plate having side edge portions turned back to engage under the free edge portions of the anchor plate, the coupling plate being of a length to be engaged at its respective ends by said upstanding portion and latch portion of the anchor plate when the top-lift is in correct position on the body member.

3. A fastening device for releasably securing a top-lift to a heel body, comprising an anchor plate with upturned edge portions at the ends thereof and free edges along the sides thereof, one end portion of said plate being of reduced width and forming a stiffly resilient tongue, and a coupling plate adapted to slide on the upper face of said anchor plate, said coupling plate having turned-back retaining elements adapted to engage under adjacent side edge portions of the anchor plate to hold the plates together face to face, said coupling plate being of a length to fit between said upturned end portions of the anchor plate.

4. A fastening device for releasably securing a top-lift to a heel body, comprising an anchor plate with upturned edge portions at the ends thereof, one end portion of said plate being of reduced width and forming a stiffly resilient tongue, and a coupling plate adapted to slide on the upper face of said anchor plate, said coupling plate having under-turned side edge portions adapted to engage under the side edges of the anchor plate to hold the plates together face to face, said coupling plate being of a length to fit between said upturned end portions of the anchor plate, said plates being provided at their forward ends with cooperating recesses to admit a tool whereby said tongue may be sprung downwardly so that its upturned portion is clear of the forward edge of the coupling plate.

REUBEN P. GRANT.
